ELECTROMAGNETIC HORN

Wilmer Lanier Barrow, Newton, Mass., assignor
to Research Corporation, New York, N. Y., a
corporation of New York

Original application January 9, 1939, Serial No.
249,910, now Patent No. 2,316,151, dated April
13, 1943. Divided and this application Decem-
ber 10, 1941, Serial No. 422,402

19 Claims. (Cl. 250—33.63)

1

The present invention relates to electromagnetic horns. The present application is a division of application, Serial No. 249,910, filed January 9, 1939, which matured, on April 13, 1943, into Letters Patent 2,316,151.

To avoid circumlocution of language, when the horn is recited in the claims as having "exciting or absorbing means," it will be understood generically that either the horn is provided with either an exciting or absorbing antenna or the like, or else that a hollow-pipe transmission system or the like is connected to the throat of the horn. When "exciting or absorbing" is recited in the claims as positioned in the throat of the horn, it will be understood that an exciting or absorbing antenna or the like is positioned in the throat of the horn.

It is by no means true that any horn will transmit or receive any wave, and an object of the present invention is to assure the production near the mouth of a sectoral horn of a wave of the $H_{1,0}$ type; or more generally, the $H_{n,0}$ type. The type of horn known as sectoral and the $H_{n,0}$ waves will be more fully described hereinafter.

On the other hand, a plurality of different types of horn waves may be generated, depending upon the configuration of the exciting means in the throat of the horn, or upon the nature of the waves delivered thereby by a hollow-pipe transmission system, and also upon the flare angle ϕ_0 and the cut-off length ρ_0 from the apex to the throat, or small or reflecting end, or the back of the horn. Special cases may arise wherein several wave-types may be used simultaneously. In many applications, however, a single wave should obtain near the mouth of the horn, as the radiation pattern will be distorted by the presence of other waves.

A further object, therefore, is to exclude waves of other types than those above described in the sectoral horn.

To the attainment of these ends, it is desirable to position the exciting or absorbing means properly, or properly to design the size of the throat of the sectoral horn, or both.

Another object is to provide a sectoral horn having a predetermined performance.

In an electromagnetic horn provided with a pair of oppositely disposed flaring sides substantially normal, and a pair of oppositely disposed sides substantially parallel, to the lines of electric intensity of desired H waves having a radial component of magnetic intensity but no radial component of electric intensity in the horn, another object of the present invention is to assure

the production of the desired H waves near the mouth of the horn and to exclude other than the desired waves.

Other and further objects will be explained hereinafter and will be particularly pointed out in the appended claims.

The invention will now be described in connection with the accompanying drawings, in which Fig. 1 is a perspective, partly broken away, of a sectoral electromagnetic horn embodying the invention, and fed by a hollow-pipe line; Figs. 2 and 3 are similar perspectives of modifications; and Fig. 4 is a diagrammatic perspective of a sectoral horn, disposed in Cartesian and cylindrical systems of co-ordinates, and carrying symbols useful in describing the invention.

The horn 16 is illustrated as of rectangular cross section, flaring smoothly and continuously from the throat to a mouth or aperture or large end of the horn, at its front. The principal or central axis of the horn extends between the smaller and larger ends of the horn. At its throat, it is shown, in Figs. 1 and 2, connected to a hollow-pipe transmission system comprising an elongated hollow pipe or tubular body portion or section 18 that is connected to the throat of the horn so as to extend over any desired distance from the horn, to the left. In Fig. 3, the horn is shown unprovided with the hollow pipe 18.

The horn may be constituted of a formed sheet of conducting material, like metal, such as copper or aluminum, or it may be constituted of other material if its inner wall is otherwise rendered a conductor of the said waves. The hollow-pipe body portion 18, to which the horn 16 is connected, may be of any desired material, conducting or dielectric, or it may otherwise be provided with an inner conducting wall. It may contain air or other gas, or it may be evacuated.

Two of the sides, shown as the top and bottom sides, may be substantially parallel, and the other two sides flared, as illustrated in Figs. 1 and 3; or the horn may be slightly pyramidal, with the sides of the horn corresponding to the said substantially parallel sides also flaring, but slightly only, as illustrated in Fig. 2. The horns of Figs. 1 and 3 may be described as of sectoral shape, and the horn of Fig. 2, as more fully explained hereinafter, may be termed substantially sectoral.

In the horn of Fig. 2, the said slightly flaring sides will, for convenience, be referred to as substantially parallel, to conform to the terminology employed in connection with the sectoral horns. Horns provided with straight sides in longitudinal cross-section, as illustrated, are economi-

cal and easy to construct. The invention is, however, applicable also to horns the sides of which are of varying flare, such as exponential or hyperbolic.

The $H_{n,0}$ waves inside these horns, at a distance several wave-lengths from the throat, are governed, among other things, by the dimensions of the parallel sides of the horn.

A projecting metal exciting or absorbing antenna rod 14 or other energy-translating apparatus is shown in Fig. 1 disposed approximately centrally in the hollow pipe 18, substantially at right angles to the axis of the horn, but it may be disposed unsymmetrically in the horn, to give a modified directive pattern for the radiant energy.

Sending apparatus (not shown) may be connected to a coaxial-line system 10, 12, or to a parallel-wire system, or to any other desired connecting system. The conductor 12 may be extended into the bell of the horn, as illustrated in Fig. 3, or into the tube 18, parallel to the top and bottom walls. In the latter case, the translating apparatus 14 is positioned in the pipe 18, at the rear of the throat of the horn. In the former case, it is positioned directly in the throat of the horn to constitute the antenna 14.

The horn of the present invention may be used for transmission or reception of ultra-high-frequency electromagnetic waves. In transmitting with the system of Fig. 1, the antenna 14 first excites electromagnetic waves in the hollow pipe, which are transmitted through the pipe 18 to the throat of the horn, and thence propagated through the horn to the mouth as "horn waves" of the $H_{n,0}$ type. At the mouth, substantially all of this energy is radiated into free space as ordinary radio waves. The horn thus constitutes a directive electromagnetic radiator. As shown in Fig. 3, however, the translating apparatus may be positioned directly in the throat of the horn, in order directly to excite the horn itself, without the use of a hollow-pipe transmission line. Substantially the same radiation pattern may be produced with either arrangement.

In receiving, a similar, but reverse, process takes place, the electromagnetic waves being received by the horn 16, and communicated to a receiving system (not shown).

The horn operates efficiently to receive substantially all of the incident energy, when used as a receiver; or, when used as a transmitter, to excite waves of the horn type, and thereby to radiate a beam of character appropriate to the horn rather than to the apparatus and the antenna itself.

An important mode or wave type is the lowest-order transversely polarized horn wave $H_{1,0}$, with the electric vector mainly parallel everywhere to the horizontal direction, obtained with an exciting rod 14 transverse to the axis and in the horizontal plane. This and the $H_{0,1}$ wave types are probably the best for sending a single beam of radiant energy and are the waves most naturally adapted for receiving.

Beams transmitted from directive antenna systems are usually accompanied by small amounts of radiation in directions other than those intended. These small amounts of radiation are referred to as secondary lobes. Beams radiated from sectoral horns may be remarkably free from secondary lobes. The configuration of the field of the $H_{n,0}$ waves, among others, inside the sectoral horn, is such that the lines of electric-field intensity are everywhere substantially parallel

to the substantially parallel sides of the horn. The flaring sides of the horn are substantially normal to the said lines of electric-field intensity. The result of this configuration is to produce substantially single-lobe beams of linear polarization in the radiated waves. These waves have constant phase on cylindrical surfaces about the axis within the horn. For this reason, the use of sectoral horns is particularly advantageous in certain kinds of applications where the shape of the beam plays an essential role in the operation. In the blind-landing of airplanes, for example, it is desirable, not only that the beam be very sharp, but also that it be peculiarly free from secondary lobes. In one such application, a smooth straight-line intersection is formed between two overlapping beams; systems of this type are commonly referred to as "equal-signal" systems. Horn radiators can provide such smooth overlapping beams without waviness or spurious components that would affect the straightness of this path of intersection. No other types of antenna has been found to produce so smooth beams with such small secondary lobes. Patterns of this character are useful also in other applications, such as direction-finding and obstacle-detection.

In general, there are two distinct groups of waves: E-waves, having a radial component of electric intensity, but no radial component of magnetic intensity, in the horn; and H-waves, having a radial component of magnetic intensity, but no radial component of electric intensity, in the horn. Two subscripts are needed to define the waves of different orders. The subscripts n and m are used, each representing a positive integer denoting the number of half-sinusoidal variations in the field between the top and bottom and the two side walls, respectively. Thus, we have the $H_{n,m}$ and the $E_{n,m}$ types of waves.

The properties of the $H_{1,0}$ wave will not be further described herein. A description thereof may be found, for example, in Reissue Letters Patent 23,003, of May 25, 1948, which makes reference to a paper by L. J. Chu and W. L. Barrow, entitled, "Electromagnetic waves in hollow metal tubes of rectangular cross section," Proceedings of the Institute of Radio Engineers, vol. 26, No. 12, December 1938, commencing at page 1520, a paper by W. L. Barrow, entitled "Electromagnetic-horn radiators," Union Radio Scientifique Internationale, No. 79, page 277, containing a revision of a paper presented at the joint meeting of the said Union and the Institute of Radio Engineers, at Washington, D. C., April 30, 1938, a paper by W. L. Barrow and L. J. Chu, entitled, "Theory of the electromagnetic horn," Proceedings of the Institute of Radio Engineers, vol. 27, No. 1, January 1939, commencing at page 51, and also a paper by W. L. Barrow and F. D. Lewis, entitled, "The Sectoral electromagnetic horn," Proceedings of the Institute of Radio Engineers, vol. 27, No. 1, January 1939, commencing at page 41.

Though the analysis will be hereinafter given in connection with sectoral horns, it applies also very approximately to horns that are somewhat pyramidal in which the two substantially parallel sides are not strictly parallel but diverge to some extent. The term "substantially sectoral" will be employed in the claims to include somewhat pyramidal horns of this nature.

The invention is not, of course, limited to the use of an exciting or absorbing rod 14. Other radiating or absorbing means, such as a vacuum tube, may also be employed, as described, for

example, in Letters Patent 2,307,011 and 2,307,012, issued January 5, 1943. As is also explained in the said Letters Patent, optimum conditions may be obtained by adjusting a piston (not shown) at the back or throat of the horn, thus to resonate or tune the throat of the horn, thereby rendering the throat of the horn more responsive to a particular frequency or a narrow band of frequencies than to other frequencies, and also in other ways.

Symbols that will be used in this specification will be understood by reference to Fig. 4. The lower of the two parallel sides of the horn of Fig. 1 is here assumed to lie in the XZ plane, with its non-parallel or flaring sides, extended, intersecting on, and making equal angles with, the Y axis. The system may be regarded as symbolizing also cylindrical co-ordinates y , ρ and ϕ . The upper parallel side of the horn is parallel to the XZ plane, and at a distance a therefrom. It is assumed that the throat of the horn is disposed along a vertical cylindrical surface having a radius ρ_0 and with its axis coincident with the Y axis. The non-parallel sides, each of length $\rho_1 - \rho_0$, are symmetrically disposed in planes perpendicular to the XZ plane, forming with the XY plane a dihedral angle equal to

$$\frac{\phi_0}{2}$$

and parallel to the lines of electric intensity of the waves propagated within the horn. The horn is regarded as having a forward direction in the positive direction of the X axis. The horizontal length of the mouth or aperture of the horn is assumed to have a value b , and the corresponding length of the throat to have a value D_0 . The symbols illustrated in Fig. 4 have, therefore, the following meaning:

ϕ_0 represents the flare angle of the horn illustrated in Fig. 1;
 b represents the horizontal dimension of the mouth or aperture of this horn, or the distance between the opposite vertically disposed sides of the horn, at the mouth of the horn;
 a represents the corresponding vertical dimension, at right angles to the horizontal dimension, or the distance between the opposite horizontally disposed sides of the horn. In the case of the slightly pyramidal horn, the dimension a should be taken at the throat of the horn. This vertical dimension is at right angles to the lines of electric intensity of the waves propagated within the horn.

ρ_1 represents the radial length of the horn, measured along one of the flaring sides, from the point or apex of the horn to the mouth or aperture; and

ρ_0 represents the cut-off length, from the said apex to the free end of the throat of the horn.

These symbols will have approximately the same or corresponding meanings in the case of pyramidal horns two of the opposite sides of which may be more or less parallel. It is convenient to measure the lengths a , b , ρ_0 and ρ_1 in terms of the wave-length λ ; they may, therefore, if the same unit of length be used for all dimensions and for the wave-length λ , be represented by the symbols

$$\frac{a}{\lambda}, \frac{b}{\lambda}, \frac{\rho_0}{\lambda} \text{ and } \frac{\rho_1}{\lambda}$$

The space wave radiated by the horn in beams of different configurations, and the response of a receiving horn to waves arriving at different

space angles, depends on the shape of the horn in all cross sections, and the configuration of the exciting system at the throat, or of the wave delivered there by the hollow-pipe transmission line. It depends also on the flare angle ϕ_0 and the cut-off length

$$\frac{\rho_0}{\lambda}$$

10 As before explained, it is an object of the present invention to design the throat or the exciting means 14, or both, so that a desired $H_{n,0}$ wave and, more particularly, an $H_{1,0}$ wave, and also, in cases, the desired wave only, shall exist in the horn, when used for transmitting; or so that the horn shall be responsive to the desired wave, such as the $H_{1,0}$ wave, or the desired wave alone, when used for receiving.

15 The $H_{1,0}$ type of wave may be excited by the current-carrying antenna rod 14 disposed centrally in the throat parallel to the XZ plane, as illustrated in Figs. 2 and 3, or by feeding an $H_{1,0}$ wave into the throat from a rectangular hollow pipe, as illustrated in Fig. 1.

20 In the $H_{1,0}$ wave, as appears from the before-mentioned papers, and as is illustrated in Figs. 8 to 10 of the said Reissue Letters Patent 23,003, of May 25, 1948, the electric lines of force lie along arcs concentric with the Y axis between the two flared sides; they have a uniform distribution along the arcs, but a half-sinusoidal distribution in the direction of the Y axis. The magnetic lines lie in planes passing through the Y axis.

25 Analysis, verified by experiment, has demonstrated that the attenuation of the $H_{n,0}$ wave is relatively large near the apex of the horn 16, which may be termed the attenuation region, but is progressively smaller at greater radial distances from the apex, which may be termed the transmission region.

30 The attenuation region obviously involves small values of ρ , and the transmission region large values of ρ , and the boundary between the two regions is not definite. The attenuation region extends from the apex outward over progressively shorter portions of the horn for increasingly large flare angles ϕ_0 . For small flare angles ϕ_0 , therefore, the attenuation region extends over large distances from the apex. As the flare angle ϕ_0 is increased, the attenuation

35 region shrinks and is confined substantially to the throat. The radial distance, from the apex radially outward, to which the region of relatively high attenuation extends, is progressively greater for waves of higher order than for waves of lower order.

40 Analysis, verified by experiment, has also established that there is a best position for the antenna rod 14, the horn 16 being carried back far enough toward the apex of the horn so as to attenuate undesirable waves and to send forth only the desired waves.

45 As explained in the said Letters Patent 2,316-151, in a horn of a given flare angle ϕ_0 , and for a given wave-length λ , a particular value for the cut-off length ρ_0 from the apex of the horn to the exciting antenna 14 may be adopted that will permit the $H_{0,1}$ wave to form and travel freely through the horn to be radiated into space from its mouth substantially unattenuated, but that

50 will effect almost complete attenuation or filtration of higher-order $H_{0,3}$, $H_{0,5}$, etc., waves during propagation from the exciting antenna toward the mouth.

55 When radiation by means of the $H_{1,0}$ wave in sectoral or slightly pyramidal horns is desired,

similarly, the higher-order $H_{3,0}$, $H_{5,0}$ . . . waves should be eliminated or filtered. Unlike the case of the $H_{0,1}$ wave, however, this wave is substantially independent of the flare angle ϕ_0 of the horn, but has a sinusoidal variation in the vertical or Y direction. In the sectoral horn, the transmission properties of the $H_{n,0}$ waves depend mainly upon the distance between the parallel, or top and bottom, surfaces of the horn. The attenuation is caused solely by decreasing the energy density as the area of the vertical cylindrical surface, coaxial with the Y axis, increases with ρ . The elimination of the higher-order waves may, in this case, therefore, be achieved by adjusting the vertical horn dimension a . The $H_{1,0}$ wave will travel freely in the radial direction through the horn when a is greater than $\lambda/2$, but for free transmission of the $H_{3,0}$ wave, a must be greater than $3\lambda/2$, and so on for higher-order waves. To eliminate the higher-order waves, therefore, the dimension a should be slightly greater than $\lambda/2$, but less than $3\lambda/2$. To eliminate the $H_{2,0}$ and $H_{4,0}$ waves in the horn, the exciting system may be constructed with even symmetry about the horizontal plane

$$\gamma = \frac{a}{2}$$

equidistant between the two upper and lower sides of the horn, as viewed in Fig. 4.

More generally, to obtain the $H_{n,0}$ wave and suppress the higher-order waves, the vertical horn dimension a , or the position of the exciting or absorbing means 14 in the horn, should be substantially between

$$n\frac{\lambda}{2} \text{ and } (n+2)\frac{\lambda}{2}$$

and to obtain the greatest amount of attenuation for the said higher-order waves, which will result in their substantial elimination, the vertical horn dimension a , or the position of the exciting or absorbing means 14 in the horn, should be substantially equal to

$$n\frac{\lambda}{2}$$

The analysis is not rigorous, and it is impossible, with present knowledge, to lay down rigorous rules or exact formulas. The formulas serve merely as a first approximation. Final adjustments must always be made, in practice, under conditions of actual operation. Variations of as much as fifty per cent, and even more, from the mathematical relations deduced theoretically, may occur, in actual practice.

Though the description above has been specifically with respect to sectoral and slightly pyramidal shapes, the same results may be obtained with a reasonable degree of accuracy, such as is usable in most engineering applications, with horn shapes that resemble the sectoral or slightly pyramidal. For example, the rectangular cross-section of these shapes may be modified slightly to have round instead of square corners, or a more or less flat or other cross-section of substantially the same shape, without altering materially the radiation pattern and the applicability of the design relations of these specifications. It is the intention of this disclosure and the appended claims to include such modifications of the invention within its scope. More specifically, in an electromagnetic horn provided with a pair of oppositely disposed flaring sides substantially normal, and a pair of oppositely disposed sides

substantially parallel, to the lines of electric intensity of desired H waves having a radial component of magnetic intensity but no radial component of electric intensity in the horn, the invention assures the production of the desired H waves near the mouth of the horn and the exclusion of other waves than those desired.

Modifications will occur to persons skilled in the art and all such are considered to fall within the scope and spirit of the invention.

What is claimed is:

1. An electromagnetic horn of substantially sectoral shape having a pair of oppositely disposed substantially parallel sides and a pair of oppositely disposed flaring sides, the angle between the flaring sides being different from the angle between the substantially parallel sides, the horn being adapted for the propagation therein of $H_{n,0}$ waves of wave-length λ having a radial component of magnetic intensity but no radial component of electric intensity in the horn, where n is a positive integer, the flaring sides being substantially normal, and the substantially parallel sides being substantially parallel, to the lines of electric intensity of the said waves within the horn, the horn having exciting or absorbing means positioned where the transverse dimension of the throat, between the substantially parallel sides of the horn, is greater than substantially $\lambda/2$.

2. An electromagnetic horn of substantially sectoral shape adapted for the propagation therein of $H_{n,0}$ waves of wave-length λ having a radial component of magnetic intensity but no radial component of electric intensity in the horn, where n is a positive integer, the horn being provided with a pair of oppositely disposed flaring sides substantially normal, and a pair of oppositely disposed sides substantially parallel, to the lines of electric intensity of the said waves within the horn, and exciting or absorbing means positioned in the throat of the horn where the transverse dimension of the throat, between the last-named pair of sides of the horn, is greater than substantially $\lambda/2$.

3. An electromagnetic horn of substantially sectoral shape having a pair of oppositely disposed substantially parallel sides and a pair of oppositely disposed flaring sides, the angle between the flaring sides being different from the angle between the substantially parallel sides, the horn being adapted for the propagation therein of $H_{n,0}$ waves of wave-length λ having a radial component of magnetic intensity but no radial component of electric intensity in the horn, where n is a positive integer, the flaring sides being substantially normal, and substantially parallel sides being substantially parallel, to the lines of electric intensity of the said waves within the horn, the horn having a cut-off throat portion the transverse dimension of which, between the substantially parallel sides of the horn, is greater than substantially $\lambda/2$.

4. An electromagnetic horn of substantially sectoral shape having a pair of oppositely disposed substantially parallel sides and a pair of oppositely disposed flaring sides, the angle between the flaring sides being different from the angle between the substantially parallel sides, the horn being adapted for the propagation therein of the lowest order, $H_{1,0}$, waves of wave-length λ having a radial component of magnetic intensity but no radial component of electric intensity in the horn, the flaring sides being substantially normal, and

the substantially parallel sides being substantially parallel, to the lines of electric intensity of the said waves within the horn, the horn having exciting or absorbing means positioned where the transverse dimension of the throat, between the substantially parallel sides of the horn, is between substantially $\lambda/2$ and $3\lambda/2$.

5. An electromagnetic horn of substantially sectoral shape adapted for the propagation therein of the lowest order, $H_{1,0}$, waves of wave-length λ having a radial component of magnetic intensity but no radial component of electric intensity in the horn, the horn being provided with a pair of oppositely disposed flaring sides substantially normal, and a pair of oppositely disposed sides substantially parallel, to the lines of electric intensity of the said waves within the horn, and exciting or absorbing means positioned in the throat of the horn, where the transverse dimension of the throat, between the last-named pair of sides of the horn, is between substantially $\lambda/2$ and $3\lambda/2$.

6. An electromagnetic horn of substantially sectoral shape having a pair of oppositely disposed substantially parallel sides and a pair of oppositely disposed flaring sides, the angle between the flaring sides being different from the angle between the substantially parallel sides, the horn being adapted for the propagation therein of the lowest order, $H_{1,0}$, waves of wave-length λ having a radial component of magnetic intensity but no radial component of electric intensity in the horn, the flaring sides being substantially normal, and the substantially parallel sides being substantially parallel, to the lines of electric intensity of the said waves within the horn, the horn having a cut-off throat portion the transverse dimension of which, between the substantially parallel sides of the horn, is between substantially $\lambda/2$ and $3\lambda/2$.

7. An electromagnetic horn of substantially sectoral shape having a pair of oppositely disposed substantially parallel sides and a pair of oppositely disposed flaring sides, the angle between the flaring sides being different from the angle between the substantially parallel sides, the horn being adapted for the propagation therein of $H_{n,0}$ waves of wave-length λ having a radial component of magnetic intensity but no radial component of electric intensity in the horn, where n is a positive integer, the flaring sides being substantially normal, and the substantially parallel sides being substantially parallel, to the lines of electric intensity of the said waves within the horn, the horn having exciting or absorbing means positioned where the transverse dimension of the throat, between the substantially parallel sides of the horn, is between substantially

$$n\frac{\lambda}{2} \text{ and } (n+2)\frac{\lambda}{2}$$

8. An electromagnetic horn of substantially sectoral shape adapted for the propagation therein of $H_{n,0}$ waves of wave-length λ having a radial component of magnetic intensity but no radial component of electric intensity in the horn, where n is a positive integer, the horn being provided with a pair of oppositely disposed flaring sides substantially normal, and a pair of oppositely disposed sides substantially parallel, to the lines of electric intensity of the said waves within the horn, and exciting or absorbing means positioned in the throat of the horn where the transverse dimension of the throat, between the

last-named pair of sides of the horn, is between substantially

$$n\frac{\lambda}{2} \text{ and } (n+2)\frac{\lambda}{2}$$

5. An electromagnetic horn of substantially sectoral shape having a pair of oppositely disposed substantially parallel sides and a pair of oppositely disposed flaring sides, the angle between the flaring sides being different from the angle between the substantially parallel sides, the horn being adapted for the propagation therein of $H_{n,0}$ waves of wave-length λ having a radial component of magnetic intensity but no radial component of electric intensity in the horn, where n is a positive integer, the flaring sides being substantially normal, and the substantially parallel sides being substantially parallel, to the lines of electric intensity of the said waves within the horn, the horn having a cut-off throat portion the transverse dimension of which, between the substantially parallel sides of the horn, is between substantially

$$n\frac{\lambda}{2} \text{ and } (n+2)\frac{\lambda}{2}$$

10. An electromagnetic horn of substantially sectoral shape having a pair of oppositely disposed substantially parallel sides and a pair of oppositely disposed flaring sides, the angle between the flaring sides being different from the angle between the substantially parallel sides, the horn being adapted for the propagation therein of $H_{n,0}$ waves of wave-length λ having a radial component of magnetic intensity but not radial component of electric intensity in the horn, where n is a positive integer, the flaring sides being substantially normal, and the substantially parallel sides being substantially parallel, to the lines of electric intensity of the said waves within the horn, the horn having exciting or absorbing means positioned where the transverse dimension of the throat, between the substantially parallel sides of the horn, is greater than a value within about fifty per cent of substantially $\lambda/2$.

11. An electromagnetic horn of substantially sectoral shape adapted for the propagation therein of $H_{n,0}$ waves of wave-length λ having a radial component of magnetic intensity but no radial component of electric intensity in the horn, where n is a positive integer, the horn being provided with a pair of oppositely disposed flaring sides substantially normal, and a pair of oppositely disposed sides substantially parallel, to the lines of electric intensity of the said waves within the horn, and exciting or absorbing means positioned in the throat of the horn where the transverse dimension of the throat, between the last-named pair of sides of the horn, is greater than a value within about fifty per cent of substantially $\lambda/2$.

12. An electromagnetic horn of substantially sectoral shape having a pair of oppositely disposed substantially parallel sides and a pair of oppositely disposed flaring sides, the angle between the flaring sides being different from the angle between the substantially parallel sides, the horn being adapted for the propagation therein of $H_{n,0}$ waves of wave-length λ having a radial component of magnetic intensity but no radial component of electric intensity in the horn, where n is a positive integer, the flaring sides being substantially normal, and the substantially parallel sides being substantially parallel, to the lines of electric intensity of the said waves within the

horn, the horn having a cut-off throat portion the transverse dimension of which, between the substantially parallel sides of the horn, is greater than a value within about fifty per cent of substantially $\lambda/2$.

13. An electromagnetic horn of substantially sectoral shape having a pair of oppositely disposed substantially parallel sides and a pair of oppositely disposed flaring sides, the angle between the flaring sides being different from the angle between the substantially parallel sides, the horn being adapted for the propagation therein of the lowest order, $H_{1,0}$, waves of wave-length λ having a radial component of magnetic intensity but no radial component of electric intensity in the horn, the flaring sides being substantially normal, and the substantially parallel sides being substantially parallel, to the lines of electric intensity of the said waves within the horn, the horn having exciting or absorbing means positioned where the transverse dimension of the throat, between the substantially parallel sides of the horn, is within about fifty per cent of a value between substantially $\lambda/2$ and $3\lambda/2$.

14. An electromagnetic horn of substantially sectoral shape adapted for the propagation therein of the lowest order, $H_{1,0}$, waves of wave-length λ having a radial component of magnetic intensity but no radial component of electric intensity in the horn, the horn being provided with a pair of oppositely disposed flaring sides substantially normal, and a pair of oppositely disposed sides substantially parallel, to the lines of electric intensity of the said waves within the horn, and exciting or absorbing means positioned in the throat of the horn where the transverse dimension of the throat, between the last-named pair of sides of the horn, is within about fifty per cent of a value between substantially $\lambda/2$ and $3\lambda/2$.

15. An electromagnetic horn of substantially sectoral shape having a pair of oppositely disposed substantially parallel sides and a pair of oppositely disposed flaring sides, the angle between the flaring sides being different from the angle between the substantially parallel sides, the horn being adapted for the propagation therein of the lowest order, $H_{1,0}$, waves of wave-length λ having a radial component of magnetic intensity but no radial component of electric intensity in the horn, the flaring sides being substantially normal, and the substantially parallel sides being substantially parallel, to the lines of electric intensity of the said waves within the horn, the horn having a cut-off throat portion the transverse dimension of which, between the substantially parallel sides of the horn, is within about fifty per cent of a value between substantially $\lambda/2$ and $3\lambda/2$.

16. An electromagnetic horn of substantially sectoral shape having a pair of oppositely disposed substantially parallel sides and a pair of oppositely disposed flaring sides, the angle between the flaring sides being different from the angle between the substantially parallel sides, the horn being adapted for the propagation therein of $H_{n,0}$ waves of wave-length λ having a radial component of magnetic intensity but no radial component of electric intensity in the horn, where n is a positive integer, the flaring sides being substantially normal, and the substantially parallel sides being substantially parallel, to the lines of electric intensity of the said

waves within the horn, the horn having exciting or absorbing means positioned where the transverse dimension of the throat, between the substantially parallel sides of the horn, is within about fifty per cent of a value between substantially

$$n\frac{\lambda}{2} \text{ and } (n+2)\frac{\lambda}{2}$$

17. An electromagnetic horn of substantially sectoral shape adapted for the propagation therein of $H_{n,0}$ waves of wave-length λ having a radial component of magnetic intensity but no radial component of electric intensity in the horn, where n is a positive integer, the horn being provided with a pair of oppositely disposed flaring sides substantially normal, and a pair of oppositely disposed sides substantially parallel, to the lines of electric intensity of the said waves within the horn, and exciting or absorbing means positioned in the throat of the horn where the transverse dimension of the throat, between the last-named pair of sides of the horn, is within about fifty per cent of a value between substantially

$$n\frac{\lambda}{2} \text{ and } (n+2)\frac{\lambda}{2}$$

18. An electromagnetic horn of substantially sectoral shape having a pair of oppositely disposed substantially parallel sides and a pair of oppositely disposed flaring sides, the angle between the flaring sides being different from the angle between the substantially parallel sides, the horn being adapted for the propagation therein of $H_{n,0}$ waves of wave-length λ having a radial component of magnetic intensity but no radial component of electric intensity in the horn, where n is a positive integer, the flaring sides being substantially normal, and the substantially parallel sides being substantially parallel, to the lines of electric intensity of the said waves within the horn, the horn having a cut-off throat portion the transverse dimension of which, between the substantially parallel sides of the horn, is within about fifty per cent of a value between substantially

$$n\frac{\lambda}{2} \text{ and } (n+2)\frac{\lambda}{2}$$

19. An electromagnetic horn adapted for the propagation therein of H waves of wave-length λ having a radial component of magnetic intensity but no radial component of electric intensity in the horn, the horn being provided with a pair of oppositely disposed flaring sides substantially normal, and a pair of oppositely disposed sides substantially parallel, to the lines of electric intensity of the said waves within the horn, and exciting or absorbing means positioned in the throat of the horn where the transverse dimension of the throat is between substantially $\lambda/2$ and $3\lambda/2$.

Certificate of Correction

Patent No. 2,467,578.

April 19, 1949.

WILMER LANIER BARROW

It is hereby certified that errors appear in the printed specification of the above numbered patent requiring correction as follows:

Column 8, line 57, claim 3, before the word "substantially", second occurrence, insert *the* ; lines 70 and 71, claim 4, strike out "there-adapted for the propagation"; column 10, line 35, claim 10, for "not" read *no*;
and that the said Letters Patent should be read with these corrections therein that the same may conform to the record of the case in the Patent Office.

Signed and sealed this 4th day of October, A. D. 1949.
